[57] CLAIM

The ornamental design for a carrier for a pair of ice skates, substantially as shown and described.

DESCRIPTION

FIG. 1 is a perspective view of a carrier for a pair of ice skates showing my new design;

FIG. 2 is a top plan view, in enlarged scale, of the carrier shown in FIG. 1;

FIG. 3 is a bottom plan view, in enlarged scale, of the carrier shown in FIG. 1;

FIG. 4 is an enlarged elevational view showing one of the two identical sides of the carrier for a pair of ice skates.

FIG. 5 is an elevational view showing one of the two identical ends thereof.

FIG. 1

FIG. 2

FIG. 3

FIG. 4
